UNITED STATES PATENT OFFICE.

WILLIAM W. HUELSTER, OF GRAND RAPIDS, MICHIGAN.

DESIGN FOR A HINGE MEMBER.

SPECIFICATION forming part of Design No. 32,901, dated July 3, 1900.

Application filed May 21, 1900. Serial No. 17,482. Term of patent 14 years.

To all whom it may concern:

Be it known that I, WILLIAM W. HUELSTER, a citizen of the United States, residing at Grand Rapids, in the county of Kent and State of Michigan, have invented and produced a new and original Design for a Hinge Member, of which the following is a specification, reference being had to the accompanying drawings, forming a part thereof.

Figure 1 is a perspective of a hinge member, showing my new design; and Fig. 2 is a plan view of the same.

As is shown in the drawings, the leading or material features of my design consist, essentially, of a plate A, having two straight edges at right angles to each other and provided with flanges B and having its remaining edges regularly curved and having near one end a curved slot D and near the other end a partially-detached portion E.

The device, as shown, consists of a flat plate A, having its edges turned at right angles to form rectilinear flanges B, arranged at right angles to each other and having a recess C

adjacent to the end of the vertical flange B. 25 One end F of the plate A is inclined about thirty degrees from the perpendicular, and its upper edge is curved on a radius extending from the angle at the junction of the flange B and the end F.

D is a segmental slot curved around the aforesaid angle as a center.

E is a portion of the plate partially detached and bent outward near its detached end and having its free end curved inward. 35 The remainder of the edge of the plate A is in the form an ogee curve.

Having thus fully described my invention, what I claim, and desire to secure by Letters Patent, is—

The design for a hinge member, as herein shown and described.

In testimony whereof I affix my signature in presence of two witnesses.

WILLIAM W. HUELSTER.
